UNITED STATES PATENT OFFICE.

JAMES THOMAS WHITTLESEY, OF LYNN, MASSACHUSETTS.

DEVICE FOR APPLYING A COATING TO ELECTRIC CONDUCTORS.

SPECIFICATION forming part of Letters Patent No. 439,916, dated November 4, 1890.

Application filed December 20, 1889. Serial No. 334,370. (No model.)

To all whom it may concern:

Be it known that I, JAMES THOMAS WHITTLESEY, a citizen of the United States, residing at Lynn, in the county of Essex and State 5 of Massachusetts, have invented certain new and useful Improvements in Devices for Applying a Coating to Electric Conductors; and I do declare the following to be a full, clear, and exact description of the invention, such 10 as will enable others skilled in the art to which it appertains to make and use the same, reference being had to the accompanying drawings, and to the letters of reference marked thereon, which form a part of this specification.

15 My invention relates to electricity, and its object is to afford a simple and effective means for applying to an electric conductor a coating of moisture-repellent substance—such as oil, grease, vaseline, tallow, soap, glycerine, or any suitable mixture, liquid or solid—for the purpose of preventing the adhesion of snow or sleet to the conductor or the formation thereon of an icy coating. While applicable to conductors of any kind, it is especially valuable in the case of overhead electric railways, in which it is desirable to maintain a good electrical contact between the conductor and the traveling contact device. It is found that the slight warmth of the conductor, due to the electric current passing through it, tends to partially melt the snow or sleet falling upon it, which causes the formation of a coating of ice, or ice and snow, that not only seriously interferes with the 25 working of the line, but endangers the safety of the conductor, which is greatly strained and liable to break by the weight of the accumulated ice and snow. By covering the conductor with a greasy or other moisture-repellent substance, the snow cannot stick to the wire, and the troubles incident to its adhesion are obviated.

My invention consists in suitable means for applying the moisture-repellent substance to the conductor, as hereinafter set forth, and particularly pointed out in the claims.

In the drawings, Figure 1 is a perspective view of one mode of carrying out my invention. Fig. 2 is a side elevation, partly in section. Fig. 3 is a cross-section of a modification, and Figs. 4, 5, and 6 show further modifications.

The drawings illustrate the invention applied to the trolley-pole of a car on an overhead electric railway. The journals *a* of the 55 trolley *A* project slightly outside of the fork *B*, in which the trolley is mounted. On these projecting ends rest the arms of the frame *C*, which extends to a suitable distance before and behind the trolley. The frame is made 60 of metal, preferably heavy sheet iron or steel, but is flexible enough to permit the arms to be spread apart when they are to be slipped over the journals *a*. The front ends of the arms are bent toward each other and united 65 by any suitable fastening—such as a thumbscrew *c*—passing through ears *c'*.

The rear ends of the frame support a pan *D* or other receptacle, firmly secured to the frame, and of such a capacity as to hold a 70 considerable supply of the moisture-repelling substance. The receptacle may be of any convenient shape and attached to the frame in any suitable manner. I have shown in Figs. 1 and 5 a pan having a curved bottom 75 and riveted to the arms of the frame, which in Figs. 1 and 2 extend along its sides at their upper edges. Inside the pan are secured two bearings *d*, in which is journaled the shaft *e* of the wheel *E*, which projects above the 80 upper edge of the pan so as to come in contact with the overhead conductor *F*. The wheel is held yieldingly against the conductor by a spring *G*, attached to the frame *C* in front of the journals *a*, preferably at the ears 85 *c'*, and connected with the trolley-pole, preferably near the crotch of the fork *B*. The spring may be provided with any of the well-known means for regulating its tension, and the arms of the frame are provided with stops—90 such as the lugs *c*²—adapted to come in contact with the trolley-pole and limit the upward movement of the wheel *E*. The pan *D* is thus kept close to the wire *F*, although the inclination of the trolley-pole may vary 95 considerably. The wheel *E* is adapted to take up the moisture-repellent substance from the receptacle and spread it upon the conductor *F*. It may be made of wood, hard rubber, or any other suitable material, and is preferably 100 grooved, as shown. It may be covered with thick felt *H* or other absorbent material, or it may be studded with bristles or wires *I*, or constructed in any way that will best enable

it to carry up and smear upon the wire the contents of the pan. In case a semi-liquid substance is used for coating, the conductor and endless belt or chain K may be passed over the wheel to assist in carrying up the grease.

To evenly distribute the moisture-repelling substance and to remove the surplus, I provide a scraper or wiper L, located behind the wheel E and pressing against the conductor. The wiper consists, preferably, of a piece of felt, notched to embrace the wire, and supported by its lower edge, preferably by means of a spring-clamp M, attached to the pan D.

15 A suitable guard is provided to prevent the contents of the receptacle from jolting out. I prefer to use two lids N, hinged to the edges of the pan and suitably notched to fit around the wheel E and wiper L. The lids may be 20 slightly dished, as indicated in dotted lines in Fig. 3, in order that drippings from the wheel and wiper may drain into the pan through the opening in which the wheel runs. It is evident that a single lid suitably slotted may be used instead of the two shown. In case it 25 is desired to apply the moisture-repelling substance to the top of the conductor, as well as to the bottom and sides, a pair of wheels E' may be mounted on either side of the pan in 30 the rear of the wheel E, arranged to distribute the grease all over the conductor. I prefer to use brush-wheels for this purpose, and to mount them horizontally in U-shaped frames O, fastened upon the lids N, though 35 they may be otherwise arranged. Their mode of action is clearly shown in Fig. 3. In case the moisture-repelling substance is in solid form—such as a bar P of tallow, soap, or the like—it can be held in a receptacle D', provided with a spring-actuated follower d' to 40 keep it in contact with the wire F. The flanges d' prevent the bar from being forced out of the receptacle when the device is removed from the wire, and yet the wire can 45 readily enter and leave the flaring upper end of the receptacle. Since the front and back of the receptacle are open, the wire can rub across the whole width of the end of the bar and so wear it away with little, if any, waste.

50 It is evident that my device may be mounted upon a special pole, instead of upon the trolley-pole, and that when so mounted it may be carried either by the car or in the hands of a person riding on the car or walking along the line. When it is not convenient to pivot the ends of the frame upon the journals of the trolley, it can be pivoted upon a collar R, secured upon the trolley-pole and provided with a shoulder r, against which may abut 60 the stop c² on the frame. In this case the two arms of the frame may be consolidated into a single arm, as shown in Fig. 5, which forks at the top to receive the receptacle D.

The modification shown in Fig. 6 consists 65 of a pair of swabs E², composed of wicking or the like, the lower ends of which dip into the oil in the pan D. The upper ends of the

wicks are pressed against the conductor F, preferably by springs S, which may be armed with spurs s to enter and hold the wicking. 70 The oil will be raised automatically by capillary attraction and applied to the conductor. When the wicks become badly worn, they can be pulled up and the useless portion trimmed off. Any number of them may be employed, 75 singly or in pairs, and a wiper L will be found useful in connection with them.

With slight modifications my invention can be applied to conductors, with which the trolley makes a top contact, traveling above 80 instead of below the wire.

The operation of my invention will be clearly understood from the drawings and the above description, and needs no further explanation.

Having thus described my invention, what I claim, and desire to secure by Letters Patent, is—

1. The combination, with an electric car, of an apparatus moving therewith for applying 90 a coating of moisture-repellent substance to the electric conductor, comprising a mechanically-operated self-feeding device adapted to move in contact with the conductor, substantially as described.

2. The combination, with a vehicle adapted to move along the line of an electric railway, of an apparatus carried by said vehicle for coating the electric conductor with a moisture-repellent substance, consisting of a receptacle for said substance containing devices for applying it to the conductor, substantially as described.

3. The combination, with a vehicle adapted to move along the line of an electric railway, 105 of an apparatus carried by said vehicle for applying to the electric conductor a moisture-repellent substance, consisting of a receptacle for said substance containing means for automatically raising it into contact with the 110 conductor, substantially as described.

4. The combination, with a pole, of a receptacle yieldingly mounted thereon and containing means for automatically applying to an electric-railway conductor a moisture-repellent coating, substantially as described.

5. The combination, with a pole, of an arm pivoted thereon, a spring supporting the arm yieldingly in relation to the pole, and a receptacle carried by the arm and containing 120 means for applying a moisture-repellent substance to an electric-railway conductor, substantially as described.

6. The combination, with a pole, of a frame pivoted thereon, a spring supporting the frame 125 yieldingly, a stop to limit the movement of the frame with relation to the pole, and a receptacle carried by said frame and containing means for applying a moisture-repellent substance to an electric-railway conductor, substantially as described.

7. The combination, with the trolley mechanism of an electric car, of a receptacle carried thereby and containing means for auto-

matically applying the contents of the receptacle to the electric conductor, substantially as described.

8. The combination, with the trolley-pole of an electric-railway car, of a receptacle for a moisture-repellent substance mounted thereon and a wheel arranged to revolve in said receptacle, substantially as described.

9. The combination, with a trolley-pole, of a frame C, pivoted thereon, a receptacle D, supported by said frame, and a wheel mounted to revolve in said receptacle, substantially as described.

10. The combination, with the trolley-pole of an electric-railway car, of the receptacle D, having a wheel mounted therein, and a wiper supported in the rear of the wheel, substantially as described.

11. The combination, with the trolley-pole of an electric-railway car, of the receptacle D, having a wheel-mounted therein and covered with a material adapted to take up the contents of the receptacle, and a wiper supported yieldingly in the rear of the wheel, substantially as described.

12. The combination, with the receptacle D, of a wheel mounted therein and a cover through which said wheel projects, substantially as described.

13. The combination, with the receptacle D, of a wheel and a wiper mounted therein, and a two-part lid N, hinged to the edges of the receptacle, substantially as described.

14. The combination, with the receptacle D, of a wheel E, mounted therein, and horizontal wheels E', mounted in the rear of the wheel E and arranged to impinge on opposite sides of an electric conductor, substantially as described.

15. The combination, with the receptacle D, of a wheel E, mounted therein, two lids N, hinged to the receptacle, and a horizontal wheel E', mounted on each lid in the rear of the wheel E, substantially as described.

In testimony whereof I affix my signature in presence of two witnesses.

JAMES THOMAS WHITTLESEY.
